CLAIM

We claim the ornamental design for a fluid container, as shown and described.

DESCRIPTION

FIG. 1 is a top, front and left side perspective view of a fluid container showing my new design;

FIG. 2 is a front elevational view thereof, the rear being identical;

FIG. 3 is a left side elevational view thereof, the right side being identical;

FIG. 4 is a top plan view thereof;

FIG. 5 is a bottom plan view thereof;

FIG. 6 is a top, front and left side perspective view of a second embodiment of FIG. 1;

FIG. 7 is a front elevational view of FIG. 6, the rear being a mirror image;

FIG. 8 is a left side elevational view of FIG. 6;

FIG. 9 is a right side elevational view of FIG. 6;

FIG. 10 is a top plan view of FIG. 6; and,

FIG. 11 is a bottom plan view of FIG. 6.
